CLAIM

The ornamental design for a vacuum bottle, as shown and described.

DESCRIPTION

FIG. 1 is a front perspective view of a vacuum bottle showing my new design;

FIG. 2 is a rear perspective view thereof;

FIG. 3 is a front view thereof;

FIG. 4 is a rear view thereof;

FIG. 5 is a left side view thereof; opposite right side view being mirror image thereof;

FIG. 6 is a top view thereof;

FIG. 7 is a bottom view thereof;

FIG. 8 is another front perspective view, wherein the upper cap is opened; and,

FIG. 9 is another rear perspective view, wherein the upper cap is opened.
